UNITED STATES PATENT OFFICE

144,931

DESIGN FOR A SOFT DRINK BAR

Albert A. Paley, Kew Gardens, N. Y., assignor to Eagle Automatic Sales Corp., New York, N. Y., a corporation of New York

Application February 20, 1945, Serial No. 118,051

Term of patent 3½ years

(Cl. D2—3)

To all whom it may concern:

Be it known that I, Albert A. Paley, a citizen of the United States, residing at Kew Gardens, in the county of Queens and State of New York, have invented a new, original, and ornamental Design for a Soft Drink Bar, of which the following is a specification, reference being had to the accompanying drawing, forming part thereof.

Fig. 1 is a front view in perspective of a soft drink bar showing my new design; and

Fig. 2 is a rear view thereof in perspective.

I claim:

The ornamental design for a soft drink bar, as shown.

ALBERT A. PALEY.
